UNITED STATES PATENT OFFICE

103,954

DESIGN FOR A COMMUNICATION BOOTH

Benjamin S. Reynolds, Madison, Wis., assignor to
Burgess Battery Company, Madison, Wis., a
corporation of Wisconsin

Application October 26, 1936, Serial No. 65,501

Term of patent 14 years

To all whom it may concern:

Be it known that I, Benjamin S. Reynolds, a citizen of the United States, residing at Madison, in the county of Dane and State of Wisconsin, have invented a new, original, and ornamental Design for a Communication Booth, of which the following is a specification, reference being had to the accompanying drawings, forming part thereof.

Fig. 1 is a perspective view and Fig. 2 is a front elevational view of a communication booth showing my design.

I claim:

The ornamental design for a communication booth as shown.

BENJAMIN S. REYNOLDS.
